Esq.; Larry J. Guffey, Esq.; Oliver & Grimsley, LLC(57) **CLAIM**

I claim the ornamental design for a word game components set, as shown and described.

DESCRIPTION

The sole FIGURE is an isometric view of a set of word game components.

Each component of the set may be rotated 180 degrees to represent alternate letters of the alphabet.

The broken lines in the drawings illustrate portions of the word game components set that forms no part of the claimed design.
